UNITED STATES PATENT OFFICE.

BERT E. ARMSTRONG, OF SEATON, ILLINOIS.

ENGINE-STARTER.

1,290,480.

Specification of Letters Patent.

Patented Jan. 7, 1919.

Application filed September 10, 1917. Serial No. 190,603.

To all whom it may concern:

Be it known that I, BERT E. ARMSTRONG, a citizen of the United States, residing at Seaton, in the county of Mercer and State 5 of Illinois, have invented certain new and useful Improvements in Engine-Starters; and I do declare the following to be a full, clear, and exact description of the invention, such as will enable others skilled in the 10 art to which it appertains to make and use the same.

My invention has for its object to provide a simply constructed and inexpensive, yet a highly efficient and durable self starting device for automobile and other internal combustion engines, and to this end, the invention resides in certain novel features of construction and unique combinations of parts to be hereinafter fully described and claimed, 15 the descriptive matter being supplemented by the accompanying drawings which form a part of this specification and in which:

Figure 1 is a side elevation of the invention applied;

Fig. 2 is a top plan view of the improved starter with the upper part of the casing removed;

Fig. 3 is a view similar to Fig. 2 but illustrating several parts in horizontal section;

Fig. 4 is practically a duplicate of Fig. 3 with the exception that it illustrates certain parts in elevation, and discloses a different position of parts; and,

Figs. 5, 6 and 7 are transverse sections on the planes indicated by the lines 5—5, 6—6 and 7—7 of Fig. 3.

Briefly speaking, the present invention comprises a starting shaft 1, starting and winding drums 2 and 3 respectively mounted 40 loosely on said shaft, a spring 4 secured at its ends to said drums, independent brakes 5 and 6 for holding the drums 2 and 3, respectively, normally against rotation, a starting clutch 7 for connecting the starting drum 2 with the shaft 1, and a winding clutch 8 for locking the winding drum 6 to said shaft.

The shaft 1 may be of any suitable formation, but as shown, the inner end of said 45 shaft is provided with a socket 9 or other suit-

able connection for operatively connecting it with the engine shaft, whereas the outer end of said shaft 1 is by preference squared at 10 for the application of a hand crank in initially winding the spring 4, or in re-winding said spring in case it should run down by accident. The drums 2 and 3 are located near the center of the shaft 1 and both of said drums are provided with inwardly extending annular flanges 11 which 55 coöperate therewith in forming a housing for the spring 4. Both drums are formed with central rectangular openings which slidably but non-rotatively receive the square hubs 12 of the movable clutch members 13 60 and 14 of the clutches 7 and 8 respectively, said members being normally spaced from the relatively fixed clutch members 15 and 16, by suitable coiled springs 17 as shown clearly in Fig. 3. As also illustrated most 65 clearly in this figure, the relatively fixed members 15 and 16 respectively of the clutches 7 and 8, are keyed to the shaft 1 for rotation bodily therewith.

A pair of transverse rock shafts 18 and 75 19 are interposed respectively between the drum 2 and the clutch member 13 and between drum 3 and clutch member 14, said shafts having cams 20 for forcing the movable clutch members 13 and 14 toward their 80 coacting clutch members 15 and 16 respectively, and also having laterally extending crank arms 20' which normally hold the brake bands 5 and 6 in contracted position, but release said bands when the shafts are 85 rocked to throw either clutch into play. Any preferred means could well be employed for holding the rock shafts 18 and 19 in inoperative position, and for operating these shafts, but for illustrative purposes, I have 90 illustrated crank arms 21 and 22 secured respectively to the shafts 18 and 19 and connected to the front ends of pull rods 23 and 24 respectively, the rear ends of said rods being pivoted to suitable foot pedals 25 and 95 26 mounted on the car, or to hand levers if occasion should so demand. Coiled springs 27 are shown connected to the crank arms 21 and 22 for normally positioning the rock shafts 18 and 19 so that their crank arms 100

21 will apply the brakes 5 and 6 and release the clutches 7 and 8. These springs, however, will easily yield when either of the foot pedals 25 or 26 is operated to either 5 start the engine or rewind the spring after starting.

All parts of the device above described, are preferably mounted in a rigid frame 28 which may be secured to the chassis of the 10 car in any preferred manner, said frame having upper and lower cover plates 29 and 30 which coöperate therewith in forming a housing for all moving parts of the starter, it being intended that this housing shall 15 contain oil so that the device will operate smoothly and easily. In this connection, it may be stated that stuffing boxes or the like will be used wherever a shaft or the like passes through the casing, but since the use 20 of such devices is well known, they have not been illustrated.

The improved starter may be applied to the machine in any suitable manner, preferably as indicated in Fig. 1, and when once 25 installed, the spring 4 must be initially wound by applying a crank to the front end of the shaft 10 and turning this shaft, after first depressing the foot pedal 26 to simultaneously release the brake band 6 and 30 throw the clutch 8 into play. It will thus be obvious that turning of the shaft 1 will, through the instrumentality of the clutch 8, rotate the drum 3, while the drum 2 is being held against rotation by its normally 35 applied brake band 5, the result being that the spring 4 is initially wound. When wound to the required extent, the foot pedal 26 is released so that the brake band 6 comes into play to hold the drum 3 against 40 rotation. When now it is desired to crank the motor by the improved starter, the foot pedal 25 is depressed with the result that the rock shaft 18 is turned to simultaneously release the brake band 5 of drum 2 and apply 45 the clutch 7 of this drum. The result is that as the spring unwinds, it rotates the drum 2, and the latter in turn drives the shaft 1 since it is connected thereto by the clutch 7. It will thus be obvious that the 50 engine will be started, and after starting thereof, the spring may again be wound to the required extent by depressing the foot pedal 26, whereupon the device will be in readiness for again starting the machine 55 whenever required.

From the foregoing, taken in connection with the accompanying drawings, it will be obvious that although my invention is of comparatively simple and inexpensive nature, it will be highly efficient and durable. Since probably the best results are obtained 60 from the specific details shown and described, such details constitute one of the

preferred types of the improved starter. It is to be understood, however, that numerous 65 minor changes may well be made without sacrificing the principal advantages. For instance, suitable adjusting means of any well known or adequate type could be employed for either tightening or loosening 70 the brake bands 5 and 6 as occasion may demand, and adjustments may well be provided to take up wear, although the latter will be reduced to a minimum since the moving parts of the device operate in oil 75 or grease within the housing provided.

I claim:

1. In an engine starter, the combination of a shaft for operative connection with the engine shaft, a pair of drums mounted 80 loosely on said shaft, a spring secured at its ends to said drums, independent friction brakes operating on the peripheries of the drums for normally holding said drums against rotation, independent clutches for 85 locking said drums to said shaft, and means for simultaneously releasing the brake for applying the clutch of either drum.

2. In an engine starter, the combination of a shaft for operative connection with the 90 engine shaft, a pair of drums mounted loosely on said shaft, a spring secured at its ends to said drums, independent brakes for normally holding said drums against rotation, independent clutches for locking said 95 drums to said shafts, a pair of transverse rock shafts extending across said first named shaft, and means on said rock shafts for simultaneously releasing the brake and applying the clutch of either drum. 100

3. In an engine starter, the combination of a shaft for operative connection with the engine shaft, a pair of drums mounted loosely on said shaft, a spring between and secured at its ends to said drums, a pair of 105 clutch members fixed on said shaft and spaced outwardly from said drums, a pair of movable clutch members on said shaft connected slidably with said drums and interposed between said drums and said fixed 110 clutch members, transverse rock shafts between said movable clutch members and said drums, independent brakes for normally holding said drums against rotation, and means on said rock shafts for simultaneously releasing the brake of either drum and forcing the movable clutch member thereof into engagement with its coacting fixed member. 115

4. In an engine starter, the combination 120 of a shaft for operative connection with the engine shaft, a pair of drums through which said shaft passes rotatably, a spring secured at its ends to said drums, independent friction brake bands surrounding said drums 125 to normally hold them against rotation, in-

dependent clutches for connecting either drum to the shaft, transverse rock shafts for operating said clutches, and lateral arms on said shafts operatively associated with 5 said brake bands for applying the brake band of either drum when the clutch thereof is disengaged.

In testimony whereof I have hereunto set my hand in the presence of two subscribing witnesses.

BERT E. ARMSTRONG.
